UNITED STATES PATENT OFFICE.

EDGAR B. SYMONS, OF MILWAUKEE, WISCONSIN, ASSIGNOR TO THE T. L. SMITH COMPANY, OF MILWAUKEE, WISCONSIN, A CORPORATION OF WISCONSIN.

DUMPING-ELEVATOR.

No. 926,909.

Specification of Letters Patent.

Patented July 6, 1909.

Application filed March 18, 1908. Serial No. 421,872.

To all whom it may concern:

Be it known that I, EDGAR B. SYMONS, residing in Milwaukee, in the county of Milwaukee and State of Wisconsin, have 5 invented new and useful Improvements in Dumping-Elevators, of which the following is a description, reference being had to the accompanying drawings, which are a part of this specification.

10 My invention has relation to improvements in automatic dumping elevators, more especially intended, although not necessarily, for dumping concrete.

In the construction of concrete buildings, 15 elevators provided with buckets for containing the concrete have been employed, in order to hoist the concrete to different floors of the building, and thereby avoid the laborious work of manually carrying the 20 concrete to the different floors where said concrete is desired to be used.

It is the object of my invention to provide an improved construction of elevators of this character in which simplicity of construction and effectiveness of operation are 25 secured, and in which certain advantageous features are present, as will be hereinafter more fully set forth.

With the above, and other incidental 30 objects in view, the invention consists of the devices and parts, or their equivalents, as hereinafter set forth.

In the accompanying drawings, Figure 1 is a side view of the complete device as 35 arranged within a building, and showing the different floors of the building in section, and furthermore showing a mixing receptacle in proximity to the apparatus; Fig. 2 is a rear view of Fig. 1, parts broken away; 40 Fig. 3 is an enlarged detail view of the lower portion of the apparatus, the channelled rail which is closest to the line of vision being omitted; Fig. 4 is a rear view of the elevator and bucket, the channelled rails being shown 45 by dotted lines; Fig. 5 is a plan view of Fig. 4; Fig. 6 is a detail view of one of the members of the mechanism for tilting the bucket; Fig. 7 is a cross section on the line 7—7 of Fig. 3; and Fig. 8 is a fragmentary 50 view of one of the channelled rails, showing the means for attaching two sections of the rail together.

Referring to the drawings, the numerals 5—9 indicate two vertical rails which are preferably channelled, or U-shaped in cross

section, with the channels facing inwardly. Guide ropes or cables for assisting in maintaining the erect position of the rails are shown in the drawings, and are advisably employed. The rails extend upwardly through 60 different floors of the building, and in order to facilitate the erection of the rails and to obviate the necessity of their being built specially for each building, and to permit of their being used in different buildings, said 65 rails are preferably made in sections placed end to end and united at the joints by plates 10 bridging over the different joints and riveted to the sections, as most clearly shown in Fig. 8. These plates are preferably L- 70 shaped in cross section, in order to afford as much stiffness as possible without materially adding to the weight, although of course channelled beams, or T-beams would answer the same purpose.

75 The elevator frame comprises the two side beams 11, 11, and a top connecting member, the latter consisting of two parallel beams 12, 12, separated slightly from each other, and having their outer ends straddling and riveted 80 to the upper ends of the side beams of the elevator frame, as most clearly shown in Fig. 5. These beams 12 are spread apart a greater distance at their centers to provide space for a pulley 13, the axis 14 of the pulley being 85 mounted in said beams. The side beams 11 of the elevator frame are preferably of a form T-shape in cross section throughout their lengths, excepting at their extreme upper ends where they are flattened to permit of 90 the attachment thereto of the beams 12. The particular T-shaped formation of the beams 11 is preferred for the reason that the stems of the T which project outwardly are made to extend into the channels of the rails 95 9, whereby the elevator frame is guided in its up and down movement.

A rope or cable 15 is connected at one end to a horizontal beam 16 in the upper portion of the building, and is extended downwardly 100 to and around the pulley 13, thence upwardly and over pulleys 16', 16', and thence downwardly to the power for operating the elevator.

105 A tiltable bucket 17 is disposed between the side beams 11 of the elevator frame, said bucket preferably having an inclined front face, a straight rear face, straight sides, and a rounded bottom. The bucket has attached to opposite sides thereof arms 18, 18. The 110

lower ends of these arms extend below the bottom of the bucket, and are provided with eyes through which pass a shaft 19, said shaft forming a pivot upon which the bucket can 5 turn. The opposite ends of this pivot shaft are supported in brackets 20, 20 which are connected to the side beams 11 of the elevator frame, and these brackets extend forwardly, and are formed at their forward ends 10 with apertured bosses which provide bearings for a forward shaft 21. The opposite ends of this shaft 21 project through the bearings and carry rollers 22, 22, which rollers bear against the forward flanges of the channeled 15 beams 11, as most clearly shown in Figs. 3, 5 and 7. Across the top of the bucket, on the rear side of said bucket, is rigidly connected an arm 23, the ends of said arm extending beyond the sides of the bucket and carrying 20 rollers 24, 24 thereon, said rollers bearing against the rear flanges of the vertical channeled rails 11. Near the lower ends of the channeled rails 11 and attached to the rear flanges thereof are cams 25, 25. Each cam 25 is similarly constructed, that is to say, is provided with a straight central portions and inclined ends or terminals.

In the room of the building in which the concrete is to be dumped, I employ a bucket 30 tilting mechanism 26, consisting of two similar arms spaced a desired distance apart, one of said arms being shown in detail in Fig. 6. Each arm is curved from its lower end upwardly to a point slightly beyond its center, and is then 35 continued in a straight extension. On one side each arm is formed with ribs 27, 27, said ribs spaced a distance apart to form a channel 28 therebetween. The arms are so disposed that the channels thereof face each 40 other. The upper rib of each arm only extends approximately one-half the distance of the lower rib, and is then preferably continued upwardly in a short straight extension 29. The lower edge of each tilting device 45 is provided medially with an apertured boss 30 to receive a pivot pin 31. The two members of the tilting mechanism, therefore, are pivotally supported, so that they can be swung from the position shown in 50 Fig. 1 to an approximately upright position. This is advantageous in that if the work on the particular floor where this particular tilting mechanism is located is suspended, and the work transferred to some floor above 55 where a similar tilting mechanism is located, it will not be necessary to remove the two members constituting the tilting mechanism at the lower floor in order to permit of the travel of the elevator and bucket to the floor 60 above, but it is only necessary to turn said pivoted members of the tilting mechanism on their pivots to an upright position, at which position, of course, they offer no impediment to the upward travel of the elevator. The 65 two members of the tilting mechanism are

supported by a horizontal support 32, said support having bearings through which the pivot pin 31 passes, and enters the apertured bosses 30 of the tilting mechanism members. The horizontal support is held rigid in any 70 desirable manner, and in the drawings I show for the purpose a brace bar 33 and a tie rod 34.

When the elevator reaches the point where it is desired to deposit the concrete, and the 75 bucket is tilted for the purpose of discharging its contents, said contents may be received into a wheelbarrow below the discharge end of the bucket, or may first be dumped into any desirable form of hopper, as, for instance, 80 a hopper similar to the hopper 35 shown in Fig. 1 of the drawings. This hopper depends from the horizontal support 32, and the lower discharge end thereof is normally closed by a curved gate 36 provided with an operating 85 handle 37, and also provided with upwardly extending wings 38 which are pivoted to the sides of the discharge end or spout of the hopper. The hopper, therefore, can be filled whenever the bucket is tilted, and a wheel- 90 barrow or other receptacle can then be run below the discharge spout of the hopper, and upon the opening of the gate 36 the contents of the hopper are of course deposited into the wheelbarrow, or other receptacle. 95

In Fig. 1 of the drawings, I have shown an ordinary form of tiltable mixing receptacle 39 which is so positioned that when the bucket is in its lowermost position and the discharge end of the receptacle is tilted downwardly, as 100 shown by dotted lines, said end of the receptacle will discharge the mixed materials into the bucket.

In the operation of the apparatus, and when the bucket is in the lower full line position shown in Fig. 1, the receptacle is tilted to the dotted line position shown in said figure. The mixed materials will then be discharged into the bucket. The receptacle is now tilted back to its original mixing position as 105 shown by the full lines. Power being now applied to the cable 15 in the proper direction, the elevator with its pivotally connected bucket is caused to travel upwardly, the lower front wheels 22 traveling along the 110 front flanges of the channeled rails 9, and the upper rear wheels 24 travel along the rear flanges of said channeled rails. The moment the upper wheels 24 strike the lower inclines of the cams 25 and ride along said 115 inclines, the bucket 17 is caused to be swung on the pivot shaft 19 in a direction to bring it from the position which it formerly occupied; and as illustrated in full lines in the lower portion of Fig. 1, to a more nearly upright position, as shown by the dotted lines. This swinging ceases when the rollers reach the straight central portions of the cams, but the bucket when the rollers are thus 120 traveling along said straight portions is 125 130

maintained in such position as to clear the discharge end of the receptacle. If this provision were not made, the bucket would project out forwardly to such an extent as to 5 strike the discharge end of the receptacle, which, of course, would interfere with the upward movement of the elevator. After the rollers leave the straight portions of the cams they descend the upper inclines of said 10 cams, and in this manner said rollers are gradually returned to their engagement with the rear flanges of the channeled rails 9. When this engagement takes place, the bucket of course necessarily tilts back to its 15 original full line position which occurs at a time when the bucket has been elevated above and clear of the discharge end of the receptacle. It will be noticed that the bucket is so pivoted that the excess weight 20 or center of gravity is forward of a vertical line drawn through the pivotal connection of said bucket with the elevator, whether the bucket is in the full line position illustrated at the lower portion of Fig. 1, or in the 25 dotted line position at said lower portion of Fig. 1, whereby the bucket is always maintained in a proper upright position, without the necessity of employing latches, or similar devices. With the continued upward movement 30 of the elevator, the bucket is finally brought to a position where the upper rollers 24 thereof enter the channels 28 of the two members of the bucket tilting mechanism 26. These rollers, therefore, with the 35 still further upward movement of the elevator ride in the channels to a point forward of the upright extension 28 of the upper rib 29, at which position the excess weight is at the rear, and the bucket thereby tilts over 40 so as to bring its upper open end into the discharging position illustrated by dotted lines at the upper portion of Fig. 1, the rollers 24, with this final tilt necessarily traveling back to a position immediately below the 45 rib extension 29. When the bucket is thus tilted it discharges its contents into the hopper 35, and from the hopper the mixed materials are finally deposited into a wheelbarrow, or other receptacle, as herein before 50 pointed out.

In the event of the elevator frame being accidentally raised after the bucket has been tilted to the dotted line discharging position, the rollers 24 will engage against the rib extensions 29, and if the lifting of the elevator were continued further, the said rollers would leave said rib extensions, and the bucket would tilt to a greater extent than that shown by the dotted lines, resulting in 55 the danger of the end of the bucket which carries the rollers 24 being brought forcibly against the channeled rails 9. In order to guard against this contingency I provide L-shaped arms 40 extending from the side 60 beams 11 of the elevator frame with which

projections 41 extending from the bucket are adapted to engage. In this manner, the extent to which the bucket can be tilted is regulated, and the bucket, even under such conditions, is held at a position where the 70 rollers 24 can again be readily brought into engagement with the rib extensions 29.

After the bucket has been emptied of its contents, the elevator frame is lowered, and this causes, first, a slight advance movement 75 of the rollers 24 in the channels 28, and then a rearward movement, the bucket by the time the rollers are leaving the lower ends of the channels being tilted back to its original position. When the elevator frame is low- 80 ered to such position that the further descent would be impeded by contact of the bucket with the discharge end of the receptacle, the rollers 24 ride up the upper inclines of the cams 25 and then on to the straight 85 portions of said cams so as to draw back or switch the bucket to such position as to clear the discharge end of the receptacle, the bucket finally resuming its normal position when the rollers 24 leave the lower inclines of 90 the cams.

As heretofore stated, the stems of the T-shaped side beams of the elevator frame extend into the channels of the rails 9. If no means were provided to guard against it, 95 there might, without resorting to further means, be considerable lateral play of the frame of the elevator; in fact, sufficient lateral play to cause the stems of the T-shaped side beams 11 to work entirely out of 100 the channels, particularly so when the bucket is at the bottom, and there is slack in the elevator cable. To prevent this, I provide the brackets 20 with outwardly extending fingers 42, 42 which fingers also extend into 105 the channels of the rails 9. I furthermore provide the upper ends of the side beams 11 with L-shaped fingers 43, 43, the outwardly extending members thereof also projecting into the channels of the rails 9. By provi- 110 sion of these additional fingers but very slight play of the elevator frame is permitted, and hence the danger alluded to is avoided. I furthermore provide stops for preventing excess tilting of the bucket when said bucket is 115 turned on its pivot to clear the discharge end of the receptacle. These stops consist of upright beams 44. The rollers 24 when they are on the straight portions of the cams only bear very slightly against these stops. 120

What I claim as my invention is:

1. In a dumping elevator, the combination of upright rails arranged adjacent to the discharge end of a mixing receptacle, an elevator frame adapted to travel up and down 125 along said rails but incapable of any lateral movement with respect to the rails, a bucket carried by the elevator frame and pivoted thereto so as to be capable of lateral movement with respect to the frame, and means 130

constructed, when the elevator starts on its upward travel, for switching or moving the bucket laterally of the elevator frame, while said elevator frame remains fixed as to any 5 lateral movement, and thereby causing the bucket to clear the discharge end of the mixing receptacle, and to also clear said discharge end of the receptacle before the bucket completes its down movement.

10 2. In a dumping elevator, the combination of upright rails arranged adjacent to the discharge end of a mixing receptacle, an elevator frame adapted to travel up and down along said rails, but incapable of any lateral 15 movement with respect to the rails, a bucket carried by the elevator frame and pivoted thereto so as to be capable of a lateral movement with respect to the frame, and means constructed, when the elevator starts on its 20 upward travel, for switching or moving the bucket laterally of the elevator frame, while said elevator frame remains fixed as to any lateral movement, and thereby causing the bucket to clear the discharge end of the mixing 25 receptacle, and to also clear said discharge end of the receptacle before the bucket completes its down movement, the pivot of the bucket being also so located that the excess weight or center of gravity of the 30 bucket, during the travel of the elevator frame up and down the rails, and also when the bucket is switched so as to clear the discharge end of the mixing receptacle, will be forward of a vertical line drawn through the 35 pivotal point of the bucket.

3. In a dumping elevator, the combination of upright rails, an elevator frame adapted to travel up and down along said rails, a bucket carried between the sides of the elevator 40 frame, a pivot shaft passing freely through ears or bearings at the lower end of the bucket, brackets connected to the sides of the elevator frame and projecting forwardly therefrom, and in the rear ends of 45 which brackets the pivot shaft is supported, a shaft journaled in the forward ends of said brackets, rollers carried at the ends of said shaft and bearing against the front faces of the upright rails, and rollers mounted on the 50 ends of axes projecting laterally from the upper end of the rear side of the bucket, said rollers adapted to bear against the rear faces of the upright rails.

4. In a dumping elevator, the combination 55 of upright rails U-shaped or channeled in cross section, the channels of the respective rails facing each other, an elevator frame, the side beams thereof being of T-shaped form in cross section, with the stems 60 of the T's projecting into the channels of the rails, a bucket carried between the side members of the elevator frame, a pivot shaft passing freely through ears or bearings at the lower end of the bucket, brackets connected 65 to the heads of the T-shaped side members of

the elevator frame and projecting forwardly therefrom, and in the rear ends of which brackets the pivot shaft is supported, a shaft journaled in the forward ends of said brackets, rollers carried at the ends of said shaft 70 and bearing against the forward flanges of the upright rails, and rollers mounted on the ends of axes projecting laterally from the upper end of the rear side of the bucket, said rollers adapted to bear against the rear flanges of 75 the upright rails.

5. In a dumping elevator, the combination of upright rails U-shaped or channeled in cross section, the channels of the respective rails facing each other, an elevator frame, the side members thereof being of T-shaped form in cross section, with the stems of the T's projecting 80 into the channels of the rails, a bucket carried between the side members of the elevator frame, a pivot shaft passing freely through ears or bearings at the lower end of the bucket, brackets connected to the heads of the T-shaped side members of the elevator frame, and projecting forwardly therefrom, and in the rear ends of which brackets the pivot shaft is supported, a shaft journaled in the forward ends of said brackets, rollers carried at the ends of said shaft 85 and bearing against the forward flanges of the upright rails, rollers mounted on the ends of axes projecting laterally from the upper end of the rear side of the bucket, said rollers adapted to bear against the rear flanges of 90 the upright rails, and fingers projecting outwardly from the upper ends of the side members of the elevator frame and into the channels of the rails, said fingers being spaced a distance apart laterally from the stems of the 95 T-shaped side members of the elevator frame.

6. In a dumping elevator, the combination of rails U-shaped or channeled in cross section, the channels of the rails facing each other, an elevator frame adapted to travel up and down the upright rails, the sides of said frame being T-shaped in cross section, with the stems of the T's projecting outwardly and into the channels of the rails, and fingers projecting outwardly from the upper ends of the side members of the elevator frame and into the channels of the rails, said fingers being 100 spaced a distance apart laterally from the stems of the T-shaped side members of the elevator frame.

7. In a dumping elevator, the combination of upright rails, an elevator frame adapted to travel up and down said rails, an elevator bucket carried between the side members of the elevator frame, a pivot shaft having its ends supported in brackets secured to the side members of the elevator frame, said shaft 105 adapted to pass freely through ears or bearings at the lower end of the elevator bucket, another shaft mounted in forward extensions of the brackets, said shaft carrying on its ends rollers adapted to bear against the for- 110 115 120 125 130

ward faces of the upright rails, rollers carried at the ends of axes projecting outwardly from the upper end of the rear side of the bucket, said rollers adapted to bear against the rear faces of the upright rails, and cams secured to the rear sides of the upright rails, said cams formed with inclined ends and with straight central portions between said ends, and adapted when the elevator frame has been raised or lowered to a certain position to receive thereon the bearing of the upper rollers, and thereby move or switch the bucket rearwardly out of its normal position.

8. In a dumping elevator, the combination of upright rails, an elevator frame adapted to travel up and down said rails, an elevator bucket carried between the side members of the elevator frame, a pivot shaft having its ends supported in brackets secured to the side members of the elevator frame, said shaft adapted to pass freely through ears or bearings at the lower end of the elevator bucket, another shaft mounted in forward extensions of the brackets, said shaft carrying on its ends rollers adapted to bear against the forward faces of the upright rails, rollers carried at the ends of axes projecting outwardly from the upper end of the rear side of the bucket, said rollers adapted to bear against the rear faces of the upright rails, cams secured to the rear sides of the upright rails, said cams formed with inclined ends and with straight central portions, and adapted when the elevator frame has been raised or lowered to a certain position to receive thereon the bearing of the upper rollers and thereby move or switch the bucket rearwardly out of its normal position, and stops arranged to the rear of the cams, and adapted to be contacted with by the upper rollers of the bucket, when said bucket is switched or moved rearwardly with too great force.

9. In a dumping elevator, the combination of upright rails, an elevator frame adapted to travel up and down said rails, an elevator bucket carried between the side members of the elevator frame, a pivot supported by the elevator frame and loosely engaging the elevator bucket so as to permit said bucket to turn thereon, rollers at the upper and lower ends of the elevator bucket, the upper rollers adapted to bear against the rear faces of the upright rails, and the lower rollers adapted to bear against the forward faces of the upright rails, and cams secured to the rear sides of the upright rails, said cams formed with inclined ends and with straight central portions between said ends, and adapted, when the elevator frame has been raised or lowered to a certain position, to receive thereon the bearing of the upper rollers, and thereby move or switch the bucket rearwardly out of its normal position.

10. A bucket dumping mechanism for

bucket carrying elevators, consisting of two medially pivoted and upwardly curved arms, spaced a distance apart laterally, each arm provided on one face and longitudinally thereof with a channel, the channels of the two arms facing each other.

11. The combination of upright rails, an elevator frame adapted to travel up and down said rails, a bucket carried between the side members of said frame, a pivot shaft having its ends supported in brackets, secured to the side members of the elevator frame, said shaft adapted to pass freely through ears or bearings at the lower end of the elevator bucket, another shaft mounted in forward extensions of the brackets, said shaft carrying on its ends rollers adapted to bear against the forward faces of the upright rails, rollers carried at the ends of axes projecting outwardly from the upper end of the rear side of the bucket, said rollers adapted to bear against the rear faces of the upright rails, and bucket dumping mechanism located at the point where the contents of the bucket are to be discharged, said mechanism consisting of two upwardly curved arms spaced a distance apart laterally, each arm provided on one face and longitudinally thereof with a channel, the channel of the two arms facing each other, and said channels when the elevator has been raised a certain distance adapted to receive the upper rollers of the bucket therein, and thereby effect the dumping of the bucket.

12. The combination of upright rails, an elevator frame adapted to travel up and down said rails, a bucket carried between the side members of said frame, a pivot shaft having its ends supported in brackets secured to the side members of the elevator frame, said shaft adapted to pass freely through ears or bearings at the lower end of the elevator bucket, another shaft mounted in forward extensions of the brackets, said shaft carrying on its ends rollers adapted to bear against the forward faces of the upright rails, rollers carried at the ends of axes projecting outwardly from the upper end of the rear side of the bucket, said rollers adapted to bear against the rear faces of the upright rails, and bucket dumping mechanism located at the point where the contents of the bucket are to be discharged, said mechanism consisting of two upwardly curved arms spaced a distance apart laterally, each arm provided on one face and longitudinally thereof with a channel, the channels of the two arms facing each other, and the upper walls of each channel being shorter than the lower wall thereof, and terminating at approximately the center of each arm, and the said channels, when the elevator has been raised a certain distance, adapted to receive the upper rollers.

of the bucket therein and thereby effect the dumping of the bucket.

13. The combination of upright rails, an elevator frame adapted to travel up and down said rails, a bucket carried between the side members of said frame, a pivot shaft having its ends supported in brackets secured to the side members of the elevator frame, said shaft adapted to pass freely through ears or bearings at the lower end of the elevator bucket, another shaft mounted in forward extensions of the brackets, said shaft carrying on its ends rollers adapted to bear against the forward faces of the upright rails, rollers carried at the ends of axes projecting outwardly from the upper end of the rear side of the bucket, said rollers adapted to bear against the rear faces of the rails, a bucket dumping mechanism located at the point where the contents of the bucket are to be discharged, said mechanism consisting of two upwardly curved arms spaced a distance apart laterally, each arm provided on one face and longitudinally thereof with a channel, the channels of the two arms facing each other, and the upper wall of the channel of each arm being shorter than the lower wall and terminating at approximately the center of each arm, and said channels, when the elevator has been raised a certain distance, adapted to receive the upper rollers of the bucket therein and thereby effect the dumping of the bucket, and stops extending from the elevator frame and adapted to limit the tilting of the bucket by contact of the projections of the bucket therewith, when the elevator frame is pulled upwardly beyond the extent desired.
14. The combination of upright rails, an elevator frame adapted to travel up and down said rails, a bucket carried between the side members of said frame, said bucket having projections depending from the lower end thereof, a pivot shaft having its ends supported in brackets secured to the side members of the elevator frame, said shaft adapted to pass freely through ears or bearings at the lower end of the elevator bucket, another shaft mounted in forward extensions of the brackets, said shaft carrying on its ends rollers adapted to bear against the forward faces of the upright rails, rollers carried at the ends of axes projecting outwardly from the upper end of the rear side of the bucket, said rollers adapted to bear against the rear faces of the rails, a bucket dumping mechanism located at the point where the contents of the bucket are to be discharged, said mechanism consisting of two upwardly curved arms spaced a distance apart laterally, each arm provided on one face and longitudinally thereof with a channel, the channels of the two arms facing each other, and the upper wall of the channel of each arm being shorter than the lower wall and terminating at approximately the center of each arm, and said channels, when the elevator has been raised a certain distance, adapted to receive the upper rollers of the bucket therein and thereby effect the dumping of the bucket, and stops extending from the elevator frame and adapted to limit the tilting of the bucket by contact of the projections of the bucket therewith, when the elevator frame is pulled upwardly beyond the extent desired.
15. A rail for bucket carrying elevators, said rail composed of sections, united at the joints by an angle iron of equal length with a rail section and extended over the joint of two sections at the back thereof and riveted or otherwise secured to said sections.
16. A rail for bucket carrying elevators, said rail composed of sections, united at the joints by an angle iron of equal length with a rail section and extended over the joint of two sections at the back thereof and riveted or otherwise secured to said sections, each angle iron being so positioned as to fall short at one end of a section and overlap at the other end thereof.

17. In testimony whereof, I affix my signature, in presence of two witnesses.

EDGAR B. SYMONS.

Witnesses:

A. L. MORSELL,
ANNA F. SCHMIDTBAUER.

18. A rail for bucket carrying elevators, said rail composed of sections, united at the joints by an angle iron of equal length with a rail section and extended over the joint of two sections at the back thereof and riveted or otherwise secured to said sections.

19. A rail for bucket carrying elevators, said rail composed of sections, united at the joints by an angle iron of equal length with a rail section and extended over the joint of two sections at the back thereof and riveted or otherwise secured to said sections, each angle iron being so positioned as to fall short at one end of a section and overlap at the other end thereof.
